UNITED STATES PATENT OFFICE.

ROBERT D. HAYES, OF NEW HAVEN, CONNECTICUT, ASSIGNOR TO INDEX VISIBLE,
INCORPORATED, OF NEW HAVEN, CONNECTICUT, A CORPORATION OF NEW
YORK.

INDEX OR FILE.

1,304,180.

Specification of Letters Patent. Patented May 20, 1919.

Application filed July 31, 1917. Serial No. 183,770.

To all whom it may concern:

Be it known that I, ROBERT D. HAYES, a citizen of the United States, residing in the city and county of New Haven and State of Connecticut, have invented certain new and useful Improvements in Indexes or Files, of which the following is a full, clear, and exact description.

This invention relates to indexes or files, and it has particular reference to a so-called visible index embodying a plurality of record holding members or cards which in the normal position are held flatwise in overlapped relation, so that only the marginal portions thereof are exposed to view.

One of the primary objects of the present invention is to provide an improved form of index card having a pocket at its free edge adapted to carry or accommodate a record slip or insert on which the record matter is directly written or typewritten, rather than on the body of the card itself.

Another object of the invention is to provide an improved index or file in which a transparent pocket extending beyond the free edge of the card body is adapted to hold a record slip or insert located at the rear of the card, the pocket being transparent at the front of the card, so that record matter on the slip or insert is visible when the cards are in the normal overlapped relation.

Another object which I have in view is the provision of an index or file in which the cards are of the downhanging or pendent type, and wherein the record slips or inserts adapted to be carried by the lower edge portions of the respective cards may be readily written or typewritten with the name or title of each item at the top of the insert, rather than at the bottom thereof as has heretofore been customary. This facilitates considerably the preparation of the inserts.

A still further object of the invention is to provide an index or file in which a transparent pocket on one card serves as a protective cover for the card behind, and wherein record matter carried by the last mentioned card can be corrected or amplified by the insertion of a record slip or insert in the pocket in front of the same.

To these and other ends, the invention consists in the novel features and combina-

tions of parts to be hereinafter described and claimed.

In the accompanying drawings,

Figure 1 is a front elevation of a portion of an index or file embodying my improvements;

Fig. 2 is an enlarged detail section on line 2-2 of Fig. 1;

Fig. 3 is a view similar to Fig. 1, showing the uppermost card raised for the inspection of the normally concealed portion of its record slip or insert;

Fig. 4 is a detail fragmentary view of the record slip or insert before it is folded;

Fig. 5 is a detail edge view of the insert after it has been folded;

Fig. 6 is a front elevation of two cards of an index of slightly modified type;

Fig. 7 is a fragmentary view of the lowermost card shown in Fig. 6; and

Fig. 8 is a detail of the insert shown in Fig. 6.

In some features the cards selected for illustration are similar to those shown in my Patent No. 1,223,168, dated April 17th, 1917, but in the present case the cards are of the downhanging or pendent type, although this is not material in most aspects of the invention. Referring particularly to Figs. 1, 2, and 3, a plurality of cards 10 are adapted to be mounted in a predetermined overlapped relation by means of tongues near the upper edges of the cards, adapted to engage a supporting strip 11 mounted on a carrier leaf 12. The tongues, supporting strip, and carrier leaf are similar to those shown in the patent above mentioned. In the present instance, the arrangement is such that the lower edge portion of each card extends downwardly below the card next in front of the same, as shown at 13 in Fig. 2. The exposed portion of the body part of each card at the lower edge thereof is protected by a transparent pocket 14 carried at the lower edge portion of the card next in front of the same. Each of the pockets extends downward beyond the lower edge of the body portion of the card by which it is carried and is adapted to accommodate a record slip or insert 15 located at the rear of the card by which the insert is carried. In making the pockets 14, I prefer to secure a strip of celestion, or other transparent material, along the lower por-

tion of each card, said strip being folded in order to create a pocket for the insert 15. In the particular form shown, a part of each strip is applied to the rear surface of the card by gluing, stitching or the like, as shown at 14^a in Fig. 2, while another part of the strip extends downward beyond the lower edge of the card body, as shown at 14^b, and a third part of the strip is folded 10 upwardly and rearwardly at the lower edge of the portion 14^b, as shown at 14^c, in order to form a retaining pocket or flange which will accommodate the insert 15. The insert is thus carried at the rear of the body portion 15 of the card and it extends downward below the lower edge of the body portion into the transparent pocket, the front wall or portion 14^b of which is partially or wholly transparent, so as to permit the reading 20 of written or typewritten matter carried by the insert 15, as shown.

The insert 15 preferably consists of a piece or slip of paper or cardboard which carries the record matter in the general disposition shown in Fig. 4, with the name or title of the particular item at the top and the detail data written below the same. The slip is then folded along the dotted line 16 near the upper margin thereof, so as to present a narrow flap 15^a at the lower part, carrying the name or title, and a larger flap or portion 15^b at the rear of the portion 15^a extending upwardly behind the body portion of the card and having the detailed data 30 located on the rear face thereof but in inverted position. Access to the detailed data on the rear face of the insert can be had by swinging the main body portion of the card in an upward direction, as shown in Fig. 3, 40 for which purpose the card is provided near the upper part thereof with a hinge 17. The hinge 17 may be of any appropriate kind. It permits the lower portion of the card, carrying the pocket, to be swung upwardly 45 into the position shown in Fig. 3, so that the detailed data on the rear face of the insert appears in its proper upright relation, in which it is readily legible.

One of the main advantages of this type 50 of index arises from the fact that the title or name of the item to which each card refers can be placed at the top of the insert when the latter is made up, rather than at the bottom thereof as has heretofore been 55 customary in card indexes of the pendent type.

In the form shown in Figs. 6, 7, and 8, the main record matter, instead of being written on an insert, is carried by the lower 60 marginal portion of the main body of the card, as shown at 18. This record member is covered by the transparent pocket on the lower edge portion of the card next in front of the first mentioned card, but as the 65 pocket is transparent the record matter is

readily visible when the cards are in the normal position. In case it is desired to correct one or more parts of the item referred to by a predetermined card, this may be done by inserting one or more inserts 19 in 70 the pocket in front of this card. Suppose that a person referred to on the body of the card as residing in Chicago, Ill., changes his residence to Philadelphia, Pa., the necessary correction can readily be made by inserting 75 in the pocket over the words "Chicago, Ill." an insert 19 on which "Philadelphia, Pa." is written. The pocket carried by one card therefore serves as a means for holding, retaining or positioning a corrective device for 80 the card lying at the rear of the same. In this case the inserts 19 can be constituted by small pieces of paper or cardboard which need not be folded, and as these can be very readily prepared there is a considerable saving of 85 time in using an index of this type, because it is not necessary to remove and discard a record member simply because one or more of its items become incorrect or out of date.

Various changes in the details of the indexes hereinafter described may obviously be made without departing from the scope of my invention as defined in the claims.

I do not claim broadly herein the combination of a support and a plurality of cards 95 mounted on said support in overlapped relation with one margin of each card exposed, each card having a transparent portion overlapping the exposed margin of the card at the rear of the same, as claimed in 100 my application, Serial No. 183,769 of even date herewith.

I claim:

1. In an index or file, the combination 105 of a support, a plurality of cards mounted on said support in overlapped relation with one margin of each card exposed, and an insert pocket on each card overlapping the exposed margin of the card at the rear of the same.

2. In an index or file, the combination of a support, a plurality of cards mounted on said support in overlapped relation with one margin of each card exposed, and a transparent pocket on each card overlapping 115 the exposed margin of the card at the rear of the same.

3. In an index or file, a plurality of overlapped cards, and transparent pockets extending beyond the free edges of the cards. 120

4. In an index or file, a plurality of overlapped cards, pockets extending beyond the free edges of the cards, and inserts in said pockets.

5. In an index or file, a plurality of overlapped cards, transparent pockets extending beyond the free edges of the cards, and inserts in said pockets visible from the front of the index through the transparent portions of the pockets.

6. In an index or file, a plurality of cards, each card having one marginal portion extending beyond the card next in front of the same so as to be exposed, a transparent portion on each card overlapping the exposed portion of the card at the rear of the same, and a record member carried by at least one of said transparent portions. 60
7. In an index or file, a plurality of overlapping flat record members, each comprising an opaque major portion, and a transparent marginal portion folded to form a pocket. 70
8. In an index or file, a plurality of cards mounted in overlapped relation and having marginal pockets at the rear thereof. 75
9. In an index or file, the combination of a support, a plurality of cards mounted on said support in overlapped relation and having free edge portions, and pockets on said cards located adjacent said free edge portions and adapted to hold record slips at the rear faces of the respective cards. 80
10. A record card for indexes or the like, having an opaque body portion, and a transparent marginal portion extending beyond the body portion and constructed to form a pocket, said pocket being provided with a longitudinal insert-receiving opening permitting inserts to project laterally therefrom. 85
11. A card for indexes and the like, having an opaque body portion, a transparent marginal portion secured to the lower edge of said body portion, and a record slip carried at the rear of said body portion by said transparent marginal portion and visible through the transparent portion. 90
12. A card for indexes or the like, having an opaque body portion, and a transparent marginal portion located beyond the body portion and folded to present a pocket at the rear of the card. 95
13. In an index or file, a plurality of cards mounted flatwise in overlapped relation with one margin of each card exposed, pockets carried by the respective marginal portions of the cards, and folded inserts in said pockets. 100
14. In an index or file, a plurality of cards mounted flatwise in overlapped relation with one margin of each card exposed, pockets carried by the respective marginal portions of the cards, and folded inserts in said pockets, said pockets being transparent and said inserts carrying record matter disposed at both the front and rear thereof. 105
15. In an index or file, a plurality of cards mounted flatwise in overlapped relation with one margin of each card exposed, 60 pockets carried by the respective marginal portions of the cards, and folded inserts in said pockets, said pockets being transparent and said inserts carrying record matter disposed at both the front and rear thereof, 65 said cards having hinged portions which can be swung into such position as to expose the record matter on the rear faces of the inserts. 70
16. In an index or file, a plurality of cards mounted flatwise in overlapped relation with one margin of each card exposed, each card carrying record matter on its exposed margin, and a corrector associated with the record matter of at least one card and carried by the card in front of the same. 75
17. In an index or file, a plurality of cards mounted flatwise in overlapped relation with one margin of each card exposed and carrying record matter, and a corrective device extending beyond one margin of at least one card and lying in front of the record matter on the card behind it. 80
18. In an index or file, a plurality of cards mounted flatwise in overlapped relation 85 with one margin of each card exposed and containing record matter, a transparent pocket extending beyond the margin of one of said cards, and a corrector in said pocket overlying certain record matter on the card 90 behind. 95
19. In an index or file, a plurality of cards mounted flatwise in overlapped relation, at least one of said cards carrying record matter on the exposed marginal portion thereof, a member extending beyond the marginal portion of the card in front of said first card, and a corrector slip carried by said member. 100
20. In an index or file, a plurality of cards mounted flatwise in overlapped relation, at least one of said cards carrying record matter on the exposed marginal portion thereof, a member extending beyond the marginal portion of the card in front of said first card, and a corrector slip carried by said member, said member constituted by a transparent strip folded to form a pocket in which said corrector slip is inserted. 105
21. In an index or file, a card transparent throughout at least a portion of its area, and a record slip on the back of the card visible through said transparent portion. 110

In witness whereof, I have hereunto set my hand on the 30 day of July, 1917.

ROBERT D. HAYES:
